RACING HORSE SHOE

John W. Burton, Tujunga, Calif.

Application March 29, 1954, Serial No. 419,343

5 Claims. (Cl. 168—24)

This invention relates to horseshoes and particularly to shoes for racing horses. The general object of the invention is to provide a shoe which, while affording maximum traction, through penetration of the track surface by the shoe, will maintain the heel portion of the horse's hoof at maximum elevation while tilting the toe portion downwardly. This attitude of ground contact is beneficial and desirable in that it tends to facilitate the attainment of higher speed with less effort on the part of the horse.

A further object is to provide a shoe which combines the foregoing functional advantages in an extremely light-weight structure; minimum weight being another essential requirement of a racing shoe.

A further object is to provide such a racing shoe which can be fabricated relatively inexpensively.

A further object is to provide such a shoe which supports the hoof at the periphery thereof and relieves sole pressure (pressure against the inner area of the hoof).

Other objects will become apparent in the ensuing specifications and appended drawings in which:

Fig. 1 is an inverted plan view of a racing shoe, particularly adaptable for dirt tracks, embodying the invention;

Fig. 2 is a rear end view of the same;

Fig. 3 is a longitudinal sectional view thereof taken on the line 3—3 of Fig. 1;

Fig. 4 is a fragmentary sectional view of the same taken transversely through the middle of one side arm of the shoe as indicated by line 4—4 of Fig. 3;

Fig. 5 is a fragmentary sectional view through the heel tip of an arm of the shoe taken on the line 5—5 of Fig. 1; and

Fig. 6 is an inverted plan view showing a modified form of the invention, especially adapted for use as a training plate.

Referring now to the drawings in detail, I have shown in Figs. 1—5, as an example of one form in which the invention may be embodied, a racing shoe suitable for dirt tracks, of somewhat elongated proportions; and in Fig. 6 I have shown a shoe better adapted for use as a training plate, and of somewhat modified proportions.

Referring first to Fig. 1, my improved racing shoe comprises generally a thin web 10 as the inward part of the shoe and a rim 11 projecting downwardly from the periphery of web 10, both the web and the rim extending continuously from one heel extremity (tip) 12 to the other.

The shoe includes a toe area 13, two lateral areas 14 and two heel areas 15.

In cross section, web 10 is quite thin and projects radially inwardly from the upper extremity of rim 11, lying substantially in a common plane but having an upper face 16 which is slightly frusto-conical, having a slight downward slope from the outer margin to the inner margin thereof as best illustrated in Fig. 4. The slight downward and inward slope of upper face 16 provides a concavity which relieves sole pressure (pressure of the shoe against the under-surface of the horse's hoof, except at the periphery of the hoof).

Flange 11 has an underface (land) 17 which, at any

2

vertical section of the shoe, is substantially parallel to the general plane of flange 10.

The invention is characterized particularly by the following proportioning of web 10 and rim 11 from the toe to the heel of the shoe: (1) the width of land 17 increases progressively from a minimum width at 17a at the toe of the shoe to maximum width at 17b at heel tips 12; (2) the depth of rim 11 decreases progressively from maximum depth at the toe of the shoe to minimum depth at the heel tips 12; (3) the width of web 10 decreases progressively from the toe of the shoe to the heel areas 15, where the extremities of the web are cut away on a bias, as at 18, to leave the extremities of rim 11 projecting to constitute the heel tips 12; (4) the outer peripheral face 19 of rim 11 is beveled downwardly and inwardly at side and heel areas 14 and 15 as shown in Figs. 4 and 5, but is vertical at the toe area, 13, as shown at 19a in Fig. 3.

The inner lateral face 20 of rim 11 is beveled downwardly and outwardly, so that in cross-section the rim 11 may be in the form of a wedge which is truncated to provide the generally flat lower face 17.

The combination of increasing width and decreasing depth of rim 11 from toe to heel has the following advantages: the toe portion of the rim 11 is relatively deep and thin, with its lower face 17a constituting practically a knife edge for penetration of the track surface to maximum depth with maximum ease, thereby providing maximum traction at the toe of the shoe. The relatively broad land faces 17b of the heel areas 15 of the shoe provide maximum penetration resisting support, whereby the heel areas 15 tend to "ride high," tending to elevate the heel portion of the horse's hoof, and to tilt the toe portion of the hoof downwardly. This facilitates the attainment of greater speed with less effort. Only a slight downward tilt is provided for, however, since the decreasing thickness of the rim 11 toward the heel tips 12 establishes a rearward convergence between the land 17 and the upper face 16, and actually, the plane of the web 14, which corresponds to the plane of the bottom of the horse's hoof when the shoe is attached, will tend to assume substantially a level position when the shoe is in penetrating engagement with a level track surface under the dead weight of a horse's quarter centered above the shoe. A further advantage of the variable penetration by rim 11 resides in increased ability to pivot at the toe area of the shoe, with the resistance to side slip gradually diminishing toward the heel.

An overall advantage resides in the combination of maximum traction in the toe area where it is most advantageous, combined with "heel lift," in a shoe having a cross section of substantially constant area throughout its arcuate extent. In this respect, the greater depth of rim 11 in the toe area 13 balances the greater width of rim 11 at the heel tips 12; and vice versa, the maximum thinness of rim 11 at the toe area balances the minimum depth of rim 11 at the heel area. Thus it is possible to fabricate the shoe from a length of material originally having substantially uniform cross section along its length. During the fabricating process, the cross sectional shape is varied without substantially varying the cross sectional area. It is therefore possible, by using a pair of geared rolls having peripheral grooves of varying cross-sectional contour corresponding to the varying cross sectional contour of the upper and lower faces of the shoe respectively, to roll a heat softened rod from a uniform cross sectional shape to the progressively varying cross sectional shape of the shoe, to thereafter sever said rod into sections each having therein, in linear succession, the various cross-sectional contours of the shoe beginning with one heel tip 12 and extending to the other tip 12; and thereafter to reheat such section and bend it into the bowed form of the shoe. For accuracy in obtaining uniformity in the final

shape of the shoe, the fabricating operations may end in an operation in which the roughly shaped shoe is beaten into a die cavity having the finish shape of the lower side of the shoe.

Fig. 6 illustrates a slight modification of the invention, in a training plate of more nearly circular shape and shorter than the shoe of Fig. 1. Fig. 6 also illustrates that in a training plate, the width of the bottom face 17' of rim 11' may be slightly wider than the toe area 13, and the width of web 10 in the toe area may be correspondingly slightly less. The proportions in the heel extremities are substantially the same as in Fig. 1. This slightly broader face is better for running on turf where the shoe is to be used as a training plate; whereas the shoe of Fig. 1, with its rim 11 of more nearly knife edge form in the toe area 13, is more adaptable for dirt tracks.

In attaching a shoe to the horse's hoof, horseshoe nails are driven through apertures 21 and through the marginal areas of the hoof, in a conventional manner.

Rim 11 is of greater height than base width (width where it joins web 10) in the toe area, and of greater width than height at the heel tips.

The vertical forward face 19a at the toe of the shoe increases the "dig" or penetration of the toe area into the track, since it lessens the inclination of this forward face toward the horizontal when the horse's hoof and the shoe are tilted forwardly, with the heel lifted (a common attitude when the shoe makes initial contact with the track surface during a running operation). This feature eliminates eighty-five percent of the slippage experienced in the use of conventional racing shoes on dirt tracks.

I claim:

1. In a shoe for racing horses, having heel tips and a

toe area, comprising: a thin web lying generally in a horizontal plane when the shoe is in a rest position in full contact with the ground; and a rim, said rim projecting downwardly from the periphery of said web throughout the circumferential extent thereof in said rest position, the depth of said downward projection below the underface of said web decreasing progressively from said toe area to said heel tips and said rim having as its underface, a ground-engaging land which varies in width progressively and gradually throughout the arcuate extent of the shoe, from minimum width at said toe area to maximum width at said heel extremities.

2. A shoe as defined in claim 1, wherein said rim is of substantially knife edge section at said toe area.

3. A shoe as defined in claim 1, wherein said rim is of greater height than base width at said toe area and is of greater width than height at the heel tips.

4. A shoe as defined in claim 1, wherein said rim is of substantially knife edge section and of greater height than base width at said toe area and has a height only slightly greater than the thickness of said web at said heel tips.

5. A shoe as defined in claim 1, wherein the forward face of the toe portion of said rim is disposed at right angles to the general plane of said web.
